UNITED STATES PATENT OFFICE.

PATRICK E. VICTORY, OF MANVILLE, RHODE ISLAND.

LOOM.

No. 821,600.

Specification of Letters Patent.

Patented May 22, 1906.

Application filed April 26, 1905. Serial No. 257,437.

To all whom it may concern:

Be it known that I, PATRICK E. VICTORY, a citizen of the United States, residing at Manville, in the county of Providence and State 5 of Rhode Island, have invented a new and useful Improvement in Looms, of which the following is a specification.

This invention has reference to an improvement in looms, and more particularly to an 10 improvement in cloth-take-up-release mechanism for looms.

Looms having weft-thread stop-motions are constructed to stop on the breaking of a weft-thread—that is to say, the power is 15 stopped; but the loom by its momentum will continue to run one or more picks, thus causing a thin place in the cloth by the loss of the weft or filling threads.

The object of my invention is to prevent 20 the occurrence of thin places in weaving cloth by the loss of one or more weft or filling threads, and I accomplish this object by providing the loom with a release mechanism which, coöperating with the take-up mechanism, operates on the starting of the loom to 25 release the take-up mechanism and allow the cloth-beam to run back the equivalent of the number of picks lost in the stopping of the loom.

30 My invention consists in the peculiar and novel construction of a release mechanism operatively connected with the weft stop-motion, the shipper-lever, and the take-up mechanism of a loom, whereby on the breaking or exhausting of a weft-thread the take-up mechanism is released and the cloth-beam run back one or more picks, as required, thereby preventing thin places in weaving cloth, as will be more fully set forth hereinafter.

40 Figure 1 is a front view of a loom provided with my improved release mechanism, showing enough of the loom to clearly locate my invention. Fig. 2 is an enlarged detail view showing a portion of the left side frame supporting the breast-beam, the pawls and ratchet of the take-up mechanism, and the left-hand end of my improved release mechanism. Fig. 3 is an enlarged detail sectional view of the right-hand end of the release 45 mechanism looking down on the same. Fig. 50 4 is an enlarged detail sectional view taken on line X X of Fig. 3, showing the actuating-latch on the shipper-lever in its normal position in full lines and in the position it would

assume in passing the operating-lever when 55 the shipper-lever is released to stop the loom in broken lines. Fig. 5 is a detail sectional view similar to Fig. 4, showing the position the actuating-latch would assume to raise the operating-lever on the return of the shipper-lever to its normal position in starting the loom; and Fig. 6 is an enlarged detail sectional view taken on line Y Y of Fig. 2 through the adjustable stop-pawl of the release mechanism. Fig. 7 is an enlarged detail view showing a portion of the left side frame and the breast-beam, the pawls, the ratchet-gear, and the connection from the ratchet-gear to the sand-roll. Fig. 8 is an enlarged detail view showing a portion of the 70 right-hand side frame and the breast-beam, the rock-shaft, the vertical arm and operating-lever mounted on the rock-shaft, the weighted bell-crank lever, and the shipping-lever. Fig. 9 is an enlarged detail view of a 75 portion of the lay-sword and the take-up lever, showing the connection between the two.

In the drawings, *a* indicates the breast-beam, *a'* the right side frame, *a²* the left side frame, *b* the weft-fork slide, *c* the shipper-lever, and *d* part of the take-up mechanism, of a loom. The slide *b* carries the usual weft-fork (not shown) and is operated in the usual way on the breaking of a weft-thread to move the slide forward or toward the front of 85 the breast-beam *a*. The shipper-lever *c* is released in the usual way by the knock-off bar (not shown) on the breaking of a weft-thread and is thrown automatically to the right to stop the loom. The part of the take-up mechanism *d* shown in the drawings consists of the ratchet-gear *d'*, secured to the shaft *d²*, which connects, through a train of gears *c' c² c³*, to the sand-roll *d⁷* or cloth-beam *d⁸* of the loom in the usual way. A lever *d³* 90 is pivotally secured to the outer end of the shaft *d²* and has the pawl *d⁴* pivotally secured to its upper end in a position to engage with the teeth on the ratchet-gear *d'*, as shown in Fig. 2. The lower end of the lever *d³* is operatively connected to the lay-sword *d⁵* of the loom in the usual way, as is shown in the drawings, by the link *d⁶*. The reciprocating movement of the lay-sword *d⁵* transmits a reciprocating movement through the lever *d³* 105 to the pawl *d⁴*, which takes up one tooth on the ratchet-gear *d'* for each pick of the loom. When the loom is in its usual running condition

tion, there is sufficient tension on the warp-threads to run the cloth-beam back several picks when required.

- My improved release mechanism consists 5 of a rock-shaft e , supported in bearings at each end on the front of the loom in a position to bring the shaft in front and slightly below the breast-beam a , as shown in Fig. 1. A vertical arm e' is secured to the shaft e in a 10 position to engage with the forward end of the weft-fork slide b . A vertical stop-arm e^2 is secured to the shaft e adjacent the arm e' in a position to bear on the face of the breast-beam a when in its normal position. An operating-lever e^3 is secured in a horizontal position to the right-hand end of the shaft e , the free end of the lever extending toward the rear of the loom, and a pawl e^4 is secured to the left-hand end of the shaft e in a position to engage 15 with the teeth of the ratchet-gear d' and hold the take-up mechanism d from running back when the pawl d^4 is on the back stroke. A bell-crank lever f , having the weighted end f' and the L-shaped end f^2 , (which extends 20 toward the rear of the machine,) is pivotally secured to the front of the side frame a' in a position for the weighted end f' to be supported on the upper end of the stop-arm e^2 and for the L-shaped end f^2 to engage with 25 the inner edge of the shipper-lever c , as shown in Fig. 1. A horizontal latch g , having the upper left-hand beveled surface g' , the lower right-hand beveled surface g^2 , and the square vertical shank g^3 , is supported in the bearing 30 35 g^4 on the plate g^5 , and this plate is secured to the front of the shipper-lever c in a position for the latch g to engage with the free end of the operating-lever e^3 , as shown in Fig. 3. The latch g rests on the top of the bearing g^4 40 in its normal position and has a free vertical movement. A stop-pawl h , consisting of a semicircular segment having the teeth h' on its periphery, is pivotally secured to a stud h^2 on a bracket h^3 , which in turn is secured to 45 the side frame a^2 in a position for the teeth h' to engage with the teeth of the ratchet-gear d' , as shown in Fig. 2. A plate h^4 , having the stop h^5 , is adjustably secured to the stud h^2 back of the stop-pawl h by the set-bolt h^6 , as 50 shown in Fig. 6. The stop h^5 is adjusted to allow the cloth-beam to run back one or more picks, as required. An arm h^7 is pivotally secured at one end to the stud h^2 between the bracket h^3 and the plate h^4 , the 55 free end of the arm extending toward the front of the loom back of the pawls d^4 and e^4 . A link h^8 is pivotally connected to the arm h^7 and to the pawl e^4 , and a pin h^9 is secured to the back of the pawl d^4 in a position to engage 60 with the free end of the arm h^7 , as shown in full lines in Fig. 1 and in broken lines in Fig. 2.

The ratchet-gear d' revolves in the direction of the arrow, as shown in Fig. 2, in the 65 normal running condition of the loom. This

moves the stop-pawl h out into its inoperative position away from the stop h^5 . In practice I find that the momentum of different looms varies from one to four or five picks after the power is stopped. The stop h^5 is therefore adjusted to each loom to compensate for the number of picks lost by the momentum of the loom.

In the operation of my improved release mechanism the power of the loom is stopped 75 on the breaking or exhausting of a weft-thread through the weft-fork, weft-fork hammer, and knock-off bar in the usual way. This releases and throws the shipper-lever c automatically to the right and moves the 80 weft-fork slide b toward the front of the loom. The forward end of the slide b , engaging with the arm e' , moves the arm e' and the stop-arm e^2 forward and partly rotates the rock-shaft e . This raises the operating-arm e^3 85 into its operative position, allows the weighted end f' of the bell-crank lever f to drop down between the stop-arm e^2 and the face of the breast-beam a and form a stop to hold the arm e^3 in its operative position, and simultaneously raises the pawl e^4 out of engagement 90 with the teeth of the ratchet-gear d' and through the link h^8 brings the arm h^7 into operative engagement with the pin h^9 on the back of the pawl d^4 , as shown in broken lines 95 in Fig. 2. The ratchet-gear d' is now held by the pawl d^4 . The shipper-lever c in its outward movement brings the latch g into engagement with the operating-lever e^3 . The lower beveled surface g^2 on the latch strikes 100 the operating-lever e^3 and the latch rides over the lever, as shown in broken lines in Fig. 4. The broken weft-thread is now pieced or replaced by a new weft-thread and the loom started by moving the shipper-lever c toward the loom into the position as shown in Fig. 1. This movement of the shipper-lever 105 brings the latch g again into engagement with the operating-lever e^3 . The upper beveled surface g' strikes the lever e^3 , passes under and 110 by the lever, and raises the lever, as shown in Fig. 5. This upward movement of the operating-lever e^3 rotates the rock-shaft e still farther and through the pawl e^4 , the link h^8 , the arm h^7 , and the pin h^9 raises the pawl d^4 out 115 of engagement with the teeth on the ratchet-gear d' and releases the take-up mechanism. The ratchet-gear d' through the tension of the warp-threads now revolves backward and allows the cloth on the cloth-beam to 120 run back the number of picks lost, and this operation is governed by the stop-pawl h engaging with the ratchet-gear d' and allowing the ratchet-gear to move back only the number of teeth or picks required, which are 125 limited by the stop-pawl h engaging with the stop h^5 . When the latch g has passed the operating-lever e^3 in starting the loom, the shipper-lever c engages with the L-shaped end f^2 of the bell-crank lever f and raises the 130

weighted end f' into its normal position. The stop-arm e^2 now passes under the weighted end f' and the pawls d^4 and e^4 assume their normal operative position on the ratchet-gear d' , as shown in full lines in Fig. 2.

Having thus described my invention, I claim as new and desire to secure by Letters Patent—

1. In a loom, a release mechanism comprising a rock-shaft, a vertical arm on the rock-shaft adapted to engage with the weft-fork slide, a horizontal arm on the rock-shaft, a latch on the shipper-lever adapted to raise the horizontal arm and partly rotate the rock-shaft, a pawl on the rock-shaft engaging with the ratchet-gear of the take-up mechanism, the ratchet-gear, the take-up mechanism, means for connecting the pawl on the rock-shaft with the pawl of the take-up mechanism, and means for limiting the reverse movement of the ratchet-gear, whereby on the starting of the loom the take-up mechanism of the loom is released and the cloth allowed to run back the equivalent of the number of picks lost, as described.

2. In a loom, a release mechanism comprising a rock-shaft, a vertical arm on the rock-shaft adapted to engage with the weft-fork slide, a vertical stop-arm on the rock-shaft adapted to bear on the face of the breast-beam, a weighted bell-crank lever adapted to engage with the vertical stop-arm and the shipper-lever, a horizontal arm on the rock-shaft, a latch on the shipper-lever adapted to raise the horizontal arm and pivotally rotate the rock-shaft, a pawl on the rock-shaft engaging with the ratchet-gear of the take-up mechanism, the ratchet-gear, the take-up mechanism, the pawl of the take-up mechanism, means for connecting the pawl on the rock-shaft with the pawl of the take-up mechanism, and mechanism for limiting the reverse movement of the take-up mechanism, whereby on the starting of the loom the take-up mechanism of the loom is released and the cloth allowed to run back the equivalent of the number of picks lost, as described.

3. In a loom, a release mechanism comprising a rock-shaft, a vertical arm on the rock-shaft adapted to engage with the weft-fork slide, a horizontal arm on the rock-shaft, a latch on the shipper-lever adapted to raise the horizontal arm and partly rotate the rock-shaft, a pawl on the rock-shaft engaging with the ratchet-gear of the take-up mechanism of the loom, the ratchet-gear, a pivoted arm, a link connecting the pivoted arm with the pawl on the rock-shaft, the pawl on the rock-shaft, the pawl of the take-up mechanism, a pin on the pawl of the take-up mechanism in a position to engage with the free end of the pivoted arm, the stop-pawl, and adjustable stop, whereby on the starting of the loom the take-up mechanism of the loom is released and the cloth allowed to run back by the tension of

the warp-threads the equivalent of the number of weft-threads lost, as described.

4. In a loom, a release mechanism comprising a rock-shaft, a vertical arm on the rock-shaft adapted to engage with the weft-fork slide, a vertical stop-arm on the rock-shaft adapted to bear on the face of the breast-beam, a weighted bell-crank lever adapted to engage with the vertical stop-arm and the shipper-lever, a horizontal arm on the rock-shaft, a latch on the shipper-lever adapted to raise the horizontal arm and partly rotate the rock-shaft, a pawl on the rock-shaft engaging with the ratchet-gear of the take-up mechanism, the ratchet-gear, the take-up mechanism, means for connecting the pawl on the rock-shaft with the pawl of the take-up mechanism, the take-up mechanism, a segmental stop-pawl having teeth adapted to engage with the teeth of the ratchet-gear of the take-up mechanism, and an adjustable stop adapted to engage with the stop-pawl to limit the movement of the pawl, whereby on the starting of the loom the take-up mechanism of the loom is released and the cloth allowed to run back by the tension of the warp-threads the equivalent of the number of weft-threads lost governed by the stop-pawl, as described.

5. The combination with a loom having the weft-fork slide b , the shipper-lever c and the take-up mechanism d , of a release mechanism comprising a rock-shaft e , a vertical arm e' on the rock-shaft adapted to engage with the weft-fork slide b , a vertical stop-arm e^2 on the rock-shaft, a horizontal lever e^3 on the rock-shaft extending toward the rear of the loom, a pawl e^4 on the rock-shaft in a position to engage with the ratchet-gear of the take-up mechanism d , the take-up mechanism comprising the lever d^3 , the pawl d^4 , the gear d' and the train of gears $c' c^2 c^3$, a bell-crank lever f having the weighted end f' and the L-shaped end f^2 pivotally secured to the loom in a position for the end f' to be held by the stop-arm e^2 and the end f^2 to engage with the shipper-lever c , a latch g having the upper beveled surface g' , the lower beveled surface g^2 and the square shank g^3 supported in the bearing g^4 on the plate g^5 which in turn is secured to the shipper-lever c in a position for the latch to engage with the lever e^3 , a segmental stop-pawl h having the teeth h' and pivotally secured to a stud h^2 on a bracket h^3 which in turn is secured to the loom in a position for the teeth h' to engage with the teeth of the ratchet-gear of the take-up mechanism d , a plate h^4 having the stop h^5 and adjustably secured to the stud h^2 by the set-bolt h^6 , the stud h^2 , an arm h^7 pivotally secured to the stud h^2 , a link h^8 pivotally connecting the arm h^7 to the pawl e^4 , and a pin h^9 secured to the pawl of the take-up mechanism in a position to engage with the free end of the arm h^7 , whereby on

the starting of the loom the take-up mechanism of the loom is released and the cloth allowed to run back the equivalent of the number of weft-threads lost, as described.

5 6. In a release mechanism for looms, the combination with a shipper-lever *c* of a rock-shaft *e*, a vertical stop-arm *e*² on the rock-shaft, a horizontal lever *e*³ on the rock-shaft, a bell-crank lever *f* having the weighted end 10 *f'* and the end *f*² pivotally secured to the loom in a position for the end *f'* to be supported on the arm *e*² and the end *f*² to engage with the shipper-lever *c*, a latch *g* having the upper beveled surface *g'*, the lower 15 beveled surface *g*², and the shank *g*³ supported in the bearing *g*⁴ on the plate *g*⁵ which in turn is secured to the shipper-lever *c* in a po-

sition for the latch to engage with the lever *e*³, means for limiting the reverse movement of the take-up mechanism, and means for operatively connecting the rock-shaft with the weft-fork slide and take-up mechanism of a loom, whereby on the starting of the loom the take-up mechanism of the loom is released and the cloth permitted to run back 20 25 a predetermined number of picks, as described.

In testimony whereof I have signed my name to this specification in the presence of two subscribing witnesses.

PATRICK E. VICTORY.
